UNITED STATES PATENT OFFICE.

HENRY G. LINDERWELL, OF PORTAGE, WISCONSIN.

MAIL-BAG CATCHER.

1,201,477.

Specification of Letters Patent.

Patented Oct. 17, 1916.

Application filed February 5, 1916. Serial No. 76,464.

To all whom it may concern:

Be it known that I, HENRY G. LINDERWELL, a citizen of the United States, residing at Portage, in the county of Columbia and State of Wisconsin, have invented certain new and useful Improvements in Mail-Bag Catchers, of which the following is a specification.

This invention relates to an improved mail catcher and the principal object of the invention is to provide a receptacle which can be placed along side of the track to receive mail bags from moving trains, the receptacle being provided with an improved locking means moved to a closed position by the mail bags dropping into the receptacle and to further so construct the closure that when once closed by the mail bag dropping into the receptacle, the closure will be retained in the closed position until the locking means provided is released by a key.

Another object of the invention is to so construct this receptacle that bags may be taken from trains moving in either direction, separate compartments being provided for the trains moving in different directions but the same locking means being used for both closures.

This invention is illustrated in the accompanying drawings, wherein:

Figure 1 is a view showing the receptacle in vertical section. Fig. 2 is a view in end elevation, one side of the receptacle being broken away to show the interior construction. Fig. 3 is a top plan of the improved receptacle. Fig. 4 is an enlarged fragmentary sectional view showing the manner of operating the key for releasing the locking mechanism. Fig. 5 is a perspective view of the improved locking means. Fig. 6 is a top plan view of one of the closures.

This receptacle 10 is supported by the legs or standards 11 and is provided with an inlet mouth 12 across which there extends the partition or bumper 13. This bumper 13 extends as shown in Fig. 2 and is provided with a depending arm 14 terminating in a finger 15 for fitting into the slot 16 formed in the head 17 of the locking plunger 18. This plunger 18 is slidably mounted in the sleeve or standard 19 which supports the bumper 13 and is yieldably held in the raised position or operative position by means of spring 20. The head 17 is provided upon opposite sides of the pocket or slot 16 with teeth 21 which extend across the

inlet opening 22 formed in the standard 19 for a purpose which will be hereinafter brought out.

From an inspection of Fig. 1 it will be readily seen that this receptacle 10 is provided with the two compartments or chambers 23 and 24 upon opposite sides of the standard 19 and further that each of these compartments is provided with a closure 25 having carrying arms 26 by means of which it is connected with the supporting rod or shaft 27 extending transversely through its compartment. This shaft which carries the closure 25 is further provided with an auxiliary closure plate 28 which extends across the inlet of the receptacle and serves as a bumper or trigger for swinging the closure to the closed position indicated by dotted lines at the left of Fig. 1. A tooth 29 extends from the closure 25 and when the closure moves to the closed position will pass through the inlet opening 22 for engagement by the tooth 21 of the plunger head. It will thus be seen that the plunger forms a latch for releasably holding the closures in the closed position.

From an inspection of Figs. 2 and 4, it will be seen that the receptacle 10 is provided at one side with a key-hole opening 30 which is formed in alignment with a key-hole opening 31 in one side of the hollow standard 19 and that the plunger 18 is provided with a pin or lug 32 positioned for engagement with the key 33 when turned. Therefore when it is desired to release one or both of the closures, it is simply necessary to insert the key and after the same is in place turn the same thus engaging the lug 32 and moving the plunger or latch downwardly to release the closure or closures and permit them to be swung back to the open position. If desired a suitable door can be provided in one side of the receptacle for removal of the mail bags from the receptacle.

When in use, the receptacle is set up along side the track with the bumper 13 extending transversely of the rails. The mail sack to be delivered is suspended from the train in any suitable manner and as the train passes the station, the sack will strike the abutment 13 and be released from its support. The sack will then drop into the inlet 12 of the receptacle and upon falling into the receptacle will strike the abutment or trigger plate 28 thus swinging the closure 25 to the closed

position indicated by the dotted lines in Fig. 1. As this closure moves to the closed position, the latch finger 29 will move into engagement with the head of the latch plunger 18 and the closure will be retained in the closed position until released by moving the plunger downwardly through the medium of the key 33. It will thus be seen that the receptacle is so constructed that sacks may be taken from trains moving in either direction and further that when the closure is locked it cannot be released by unauthorized persons who desire to remove the mail sacks and further that when closed it will provide a closure which will prevent water from entering the receptacle. It will be further noted that when in the open position, the trigger plate 28 will protect the lower portion of the receptacle so that access to a sack in one of the compartments cannot be had through the second compartment. I have therefore provided a very simple device which can be used for trains moving in either direction and which is so constructed that it will be strong and durable and not liable to easily break or get out of order.

What is claimed is:

1. A mail catcher comprising a receptacle having an open inlet, a hollow standard in said receptacle, an abutment carried by said standard, said standard being provided with a side opening, a plunger slidably mounted in said hollow standard and yieldably held in a raised position and provided at its upper end with a latching head, a closure pivotally mounted in said receptacle for moving across the inlet and provided with a latching finger for passing through the opening of said standard into engagement with the latching head of said plunger, a trigger for said closure positioned for engagement with an article dropped into the closure, engagement of said trigger by the article moving the closure to a closed position in engagement with the latching plunger, and means whereby said latching plunger may be moved to an inoperative position.

2. A mail catcher comprising a receptacle, a standard in said receptacle, an abutment carried by said standard and extending through the inlet opening of said receptacle,

latching means carried by said standard and yieldably held in an operative position, closures movably mounted in said receptacle upon opposite sides of said standard, triggers for said closures extending beneath the inlet opening of said closure, said triggers when moved by an article placed in said receptacle bringing said closures to a closed position in engagement with said latching means, and means whereby said latching means may be moved to an inoperative position to release said closures.

3. A mail catcher comprising a receptacle provided with an inlet, an abutment extending across the inlet of said receptacle, latching means in said receptacle, closures movably mounted in said receptacle upon opposite sides of said latching means and provided with means for engagement by said latching means to releasably hold the closure in a closed position, and triggers for moving said closures to a closed position.

4. A mail catcher comprising a receptacle provided with an inlet, an abutment extending across the inlet of said receptacle, latch means in said receptacle, shafts extending through said receptacle, closures connected with said shafts and having their upper end portions provided with means for engagement by said latch means to releasably hold the closures in a closed position, and trigger plates extending from said shafts beneath the inlet of said receptacle when said closures are in an open position.

5. A mail catcher comprising a receptacle provided with an inlet, an abutment extending across said inlet, latch means mounted in said receptacle, a closure movably mounted in said receptacle, and a trigger for said closure positioned beneath the inlet when the closure is open, engagement of said trigger by an article entering said receptacle moving the closure into engagement with said latch means.

In testimony whereof I affix my signature in presence of two witnesses.

HENRY G. LINDERWELL.
